UNITED STATES PATENT OFFICE.

JACOB UTLEY CARTER, OF CARDSTOWN, ALBERTA, CANADA.

MAIL-BOX.

1,289,651.

Specification of Letters Patent.

Patented Dec. 31, 1918.

Application filed May 4, 1918. Serial No. 232,629.

To all whom it may concern:

Be it known that I, JACOB U. CARTER, an American citizen, of St. George, Washington Co., State of Utah, residing at Cardstown, 5 in the Province of Alberta and Dominion of Canada, have invented new and useful Improvements in Mail-Boxes, of which the following is a specification.

This invention relates to rural mail boxes 10 and it consists in the novel features herein-after described and claimed.

An object of the invention is to provide 15 a box of the character stated having a hinged lid or cover adapted to be normally locked in a closed position with relation to the body of the box but which may be unlocked without the use of a key and swung to an open position. Means are provided upon the body of the box and adapted to be manipulated by one familiar with the same for releasing the lid whereby it may be swung to an open position.

Another object of the box is to provide 25 spring means for automatically opening the lid when the same is released also the provision of an opening through the lid whereby mail may be inserted in the box and a cover which normally closes the said opening.

In the accompanying drawing:

30 Fig. 1 is a side elevation of the box.

Fig. 2 is an end elevation of the same with parts in section.

Fig. 3 is a transverse sectional view of the box.

35 Fig. 4 is a longitudinal sectional view of the same cut on the line 4-4 of Fig. 3 and showing parts broken away.

Fig. 5 is a plan view of the box with parts removed and parts in section.

40 Fig. 6 is a fragmentary plan view of a corner portion of the box with parts in section.

Fig. 7 is a side elevation of a modified form of the box.

45 Fig. 8 is a fragmentary plan view of the modified form of the box showing parts in section.

The box comprises a body 1 which may be made of metal or any other suitable material. 50 A lid 2 is hingedly connected at one edge to one side of the box and is provided with an opening 3 through which mail may be inserted into the box. The said opening 3 is surrounded at the top of the lid by a bead or flange 4. Springs 5 are located in the hinges which connect the lid 2 with the body

of the box and the said springs are under tension with a tendency to normally open the lid with relation to the body of the box when the lid is released. The lid 2 is provided at its rear side with a flange 6 adapted to engage the back of the box when the lid swings to an open position whereby the swinging movement of the lid is limited. A cover 7 is connected by means of a hinge 8 with the rear portion of the lid 2 and is adapted to lie in an inclined position over the lid and the opening 3. A securing device 9 is adapted to engage the lid 2 as best illustrated in Fig. 3 whereby the cover 7 may be temporarily secured at a fixed position with relation to the lid. When it is desired to insert mail matter into the body of the box the securing device 9 is disengaged from the lid 2 by turning the said securing device in a usual manner and consequently the cover 7 may be swung in an upward direction away from the lid and the opening 3 is uncovered, therefore pieces of mail may be inserted in the body 1 through the opening 3. After this has been done the cover 7 may be swung down over the lid 2 and secured by manipulating the securing device 9. Inasmuch as the cover 7 normally is disposed in an inclined position any rain or moisture which may fall upon the same will run off and cannot enter the body 1 through the opening 3. The lid 2 is provided at its free edge portion and at its underside with a depending lug 10 which is provided with an opening 11 through which a securing bolt (hereinafter described) may pass for the purpose of locking the lid at a closed position with relation to the body of the box. The lug 10 is provided at its lower portion with a curved edge 12.

The body 1 is provided at the exterior surfaces of its sides and ends with vertically disposed projections 13 resembling pilasters with projections 14 resembling beams located at the upper end of the intermediate and end pilasters and which circumscribe the upper edge of the body of the box. A spring 15 is concealed in one of the pilasters 13 and engages at its free end one of the beams 14 as best shown in Fig. 2 of the drawing and the said beam 14 is slideable longitudinally.

A partition 16 is located within the body 1 and extends longitudinally thereof and divides the said body into a mail receiving compartment and a lock retaining compartment. The lock comprises a guide 17

having a pin 18 passing transversely through the same. A bolt 19 is slidably mounted in the guide 17 and is provided at its side with a recess 20 which receives the 5 pin 18. The bolt is further provided with a collar or shoulder 21 against which the upper end of a spring 22 bears. The spring 22 is secured at its lower end within the body 1 of the box. The spring 22 is under 10 tension with a tendency to normally hold the bolt 19 in a projected position with relation to the guide 17. The bolt 19 is provided at its working end with a notch 23, (see Fig. 6). A spring 24 is attached to the 15 front side of the body 1 and may enter the notch 23 whereby the bolt 19 is held at a retracted position with relation to the guide 17 and against the tension of the spring 22. A cord 25 is attached at one end to the 20 end of the bolt 19 and passes through the end of the body 1 and is connected with the 25 slideable beam 14 as best shown in Fig. 6 of the drawing.

Consequently when the beam 14 is slid 25 by one who is familiar with the structure of the box the cord 25 is moved longitudinally whereby the bolt 19 is moved against the tension of the spring 22 and the said spring is flexed away from the guide 17. 30 This moves the bolt 19 to a retracted position whereby its end portion is moved out of the opening 11 in the lug 10 thereby releasing the lid 2. The lid 2 then swings to an open position under the influence of 35 the springs 5 mounted at the hinges of the said lid. Immediately thereafter the spring 24 enters the notch 23 whereby the bolt 19 is held at a retracted position. Consequently the box is opened and when the 40 contents of the box have been removed therefrom the lid is swung to a closed position whereby the curved edge 12 of the lug 10 comes in contact with the spring 24 and moves the free end thereof out of the notch 45 23. This releases the bolt 19 and under the influence of the spring 22 the end of the bolt is passed through the opening 11 in the lug 10 and securing the lid 2 at a closed position above the upper edges of the body 50 of the box. At the same time the cord 25 is moved whereby the beam 14 is drawn back to its original or normal position with relation to the body of the box.

In the form of the invention as illustrated 55 in Figs. 7 and 8 the slideable beam 14 is dispensed with and the cord 25 is trained around a pulley 26 located at one end of the body 1 and then extends through the opposite end of the body and around a pulley 60 27 and is connected with a slideable pilaster 13' located at a corner of the body 1. In

this form of the invention when it is desired to release the lid the pilaster 13' is moved in a downward direction whereby the bolt 19 is withdrawn from the lug of 65 the lid and the lid swings to an open position as hereinbefore described. When the lid is closed the bolt 19 is permitted to enter the opening in the lug and the cord 25 is moved whereby the pilaster 13' is moved up 70 to its original or normal position at the corner of the box. In both forms of the invention it is necessary for one to be familiar with the structure of the box in order to effect the opening of the lid and when so 75 familiarized the lid may be easily and quickly swung to an open position without the use of a key for it may be released from the locking device as hereinbefore described and when it is swung to a closed position 80 the bolt of the lock automatically engages the lug of the lid and holds the lid at such position.

Having described the invention what is claimed is:—

1. A mail box comprising a body, a lid hinged thereto, a spring pressed bolt slidably mounted in the box and adapted to engage the lid to hold the same at a closed position, a member movably mounted at the 90 exterior of the box and flexible means operatively connecting the bolt with said member.

2. A mail box comprising a body, a lid hinged thereto, a bolt slidably mounted in 95 the body and engageable with the lid to hold the same at a closed position upon the body, a spring bearing against the bolt, a second spring adapted to engage the bolt for holding the same at a retracted position, 100 means carried by the lid for engaging the second mentioned spring when the lid is closed to disengage the said spring from the bolt, a member movably mounted at the exterior of the body and means operatively 105 connecting said member with the bolt.

3. A mail box comprising a body, a lid hinged thereto, a bolt slidably mounted in the body and adapted to engage the lid to hold the same at a closed position, a spring 110 bearing against the bolt, a spring adapted to engage the bolt for holding the same at a retracted position, means carried by the lid for engaging the second mentioned spring to cause the same to disengage the 115 bolt, a cord attached to the bolt and trained from one end of the body to the other and a pilaster located at the exterior of the body and connected with the cord.

In testimony whereof I affix my signature. 120

JACOB UTLEY CARTER
